HOLLOW WALLED CARTON

William A. Smith, Cicero, Ill., assignor to Chicago Carton Company, Chicago, Ill., a corporation of Delaware

Application February 10, 1940, Serial No. 318,236

7 Claims. (CL 229--34)

This invention relates to an improvement in hollow or tubular walled boxes, and more particularly to boxes of that type which are capable of being folded to a flat or collapsed condition for storage and shipment purposes, and which may be readily set up by the user at the time the box is to be employed.

The main objects of the invention are to provide means for locking a tubular walled box of the character indicated in set up condition; to provide locking means for the purpose indicated which will be positive in action and which will not readily become disabled or disengaged, but which may nevertheless be easily and quickly engaged as an incident to the setting up of the folded or collapsed box; and to provide improved locking means of simple, rugged character which will not increase the size of the blank from which the box is formed.

The improved construction is primarily designed for use in connection with the manufacture of paper boxes but it will be apparent that other foldable materials may be substituted. Other objects and advantages of the invention will be understood by reference to the following specification and accompanying drawings (two sheets) wherein there is illustrated a collapsible, tubular walled box of paper construction embodying a selected form of the invention.

In the drawings:

Figure 1 is a plan of the blank from which the improved box is formed;

Figure 2 is a perspective of the completely formed box in collapsed or flattened condition;

Figure 3 is a section on the line 3--3 of Figure 2;

Figure 4 is a perspective of the improved box in set up condition;

Figure 5 is a section on the line 5--5 of Figure 4;

Figure 6 is a perspective of a corner portion of the box showing one position of the parts during the process of setting up the box;

Figure 7 is a section corresponding to Figure 5 but showing the parts in substantially the same position as illustrated in Figure 6;

Figure 8 is a perspective of a corner portion of the box in set up condition; and

Figure 9 is a plan of a corner of the box, certain portions being broken away and shown in section to more clearly illustrate the construction.

Referring now to the drawings, the improved box is formed from a blank of suitable paper-board material which is cut and provided with

fold and slit lines respectively designated F and S, so as to divide the blank into a bottom wall or panel 10 and wall forming sections 11, 12, 13 and 14. Each of the wall forming sections includes fold lines which divide the sections into outer wall forming portions or panels 15, top forming portions or panels 16, inner wall portions or panels 17 and attachment or gluing flaps 18.

The wall forming sections 12 and 14 embody slit lines and fold lines which serve to provide foldable tongues 19, 19 at each end of each of the top wall portions 16. As illustrated, the respective tongues 19 are, in effect, removed from the respective top wall portions 16 and they are foldable about foldable connections with the respective inner fold portions or panels 17, 17, such connections being spaced outwardly from the adjacent edge fold line of the top wall portion 16 (or downwardly from the top when the box is set up).

The wall forming sections 11 and 13 are respectively provided with foldable flaps 20, 20 at each end of the outer wall forming portions 15, 15. Each section 11 and 13 is also provided with a pair of tongues 21, 21 at each end of its top wall portion 16, such tongue extending integrally laterally outwardly from the respective end portions of said top wall panels.

The blank is initially folded to the collapsed box form illustrated in Figure 2, the respective wall forming sections being folded about the various fold lines so as to form the sections into collapsed tubes, the attachment flaps 18, 18 being glued or otherwise secured to the marginal portions of the bottom section 10. By preference, the fold line F between each attachment flap 18 and the adjacent inner wall panel is formed by cut scoring, i. e., by cutting partially through the thickness of the stock so as to provide for a sharp fold at that point.

When the box is to be set up, the respective walls are pressed inwardly and upwardly, the walls 12 and 14 being first adjusted to their set up, tubular position as illustrated in Figure 6. The walls 11 and 13 are then set up either simultaneously or successively. During the setting up of the walls 11 and 13, the tongues 20 are folded inwardly and guided into the interior of the tubular walls 12 and 14, and the tongues 21, 21 are also guided into the interior of the walls 12 and 14 to a position immediately below the top portions 16 of the respective walls 12 and 14. It being understood that the walls are all prefabricated to be of the same height, it will be apparent that said tongue 21 will assume the position mentioned, the adjacent end portions of the top panels

from which they extend being incidentally deflected slightly to permit the tongues to be lowered to the extent of the thickness of the paperboard stock.

The tongues 19 are folded about their respective fold lines F to a downwardly extending position in face to face engagement with the respective inner wall portions 17, thereby to permit the adjacent end edge 17a of the inner wall portion of the adjacent wall 11 to pass transversely across the downwardly folded tongue.

When the walls 11 (or 13) reach their fully set up condition as illustrated in Figures 4, 5, 8 and 9, the tongue 19 will be located within the space between the inner and outer wall portions 15 and 17 and will spring upwardly to a position against the inner surface of the top portion of the wall. As illustrated, the tongues 19 and 21 are of such width that they fit snugly within the respective walls into which they project and the innermost edges 22 of the various tongues are adapted to engage the inner surfaces of the respectively adjacent inner wall portions 17, 17, so as to thereby prevent outward or unfolding movement of the walls.

It will be observed that the foldable or bendable tongue 19 is wholly concealed within one of the tubular walls and that the inherent resiliency of the paperboard stock tends to maintain the tongue in its unfolded, laterally extended position as illustrated in Figures 5, 8 and 9. Because the tongues 19 and 21 are located entirely within the respective walls they are protected from outward forces which might tend to fold them downwardly so as to permit unfolding of the walls and it will be apparent that unfolding of the walls can be accomplished only by a very deliberate manipulation of the tongue 19.

Changes in the described construction may be made without departing from the invention, the scope of which should be determined by reference to the following claims, the same being construed with reference to the spirit of the invention rather than to the specific but alterable details of construction illustrated.

I claim:

1. A paper board box having a bottom wall and relatively transversely extending tubular side walls, said side walls being foldably connected to said bottom wall and being foldable, one in advance of the other, from collapsed condition substantially flatwise of the bottom wall to distended tubular condition in upstanding relation to said bottom wall, and means for locking one of said side walls in upstanding position comprising a tongue carried by and normally projecting laterally inwardly from the first foldable wall, said tongue being bendable to substantially non-projecting position relative to the wall from which it normally projects, the other of said walls having an end portion terminating in proximity to the plane of said tongue when bent to said non-projecting position and being adjustable to upstanding position by movement transversely past said tongue when folded to said non-projecting position, the inherent resiliency of the material of the box serving to cause said bendable tongue to spring to said normal position after movement of said wall end portion therepast, whereby said tongue is caused to project beyond said wall end portion so as to obstruct movement of said last folded wall to collapsed condition.

2. A paper board box having a bottom wall and

relatively transversely extending tubular side walls, said side walls being foldably connected to said bottom wall and being foldable, one in advance of the other, from collapsed condition substantially flatwise of the bottom wall to distended tubular condition in upstanding relation to said bottom wall, means for locking one of said side walls in upstanding position comprising a tongue carried by and normally projecting laterally inwardly from the first foldable wall, said tongue being bendable to substantially non-projecting position relative to the wall from which it normally projects, the other of said walls having an end portion terminating in proximity to the plane of said tongue when bent to said non-projecting position and being adjustable to upstanding position by movement transversely past said tongue when folded to said non-projecting position, the inherent resiliency of the material of the box serving to cause said bendable tongue to spring to said normal position after movement of said wall end portion therepast, whereby said tongue is caused to project beyond said wall end portion so as to obstruct movement of said last folded wall to collapsed condition, and means for locking the first folded wall in upstanding position.

3. A paper board box having a bottom wall and relatively transversely extending tubular side walls, said side walls being foldably connected to said bottom wall and being foldable, one in advance of the other, from collapsed condition substantially flatwise of the bottom wall to distended tubular condition in upstanding relation to said bottom wall, means for locking one of said side walls in upstanding position comprising a tongue carried by and normally projecting laterally inwardly from the first foldable wall, said tongue being bendable to substantially non-projecting position relative to the wall from which it normally projects, the other of said walls having an end portion terminating in proximity to the plane of said tongue when bent to said non-projecting position and being adjustable to upstanding position by movement transversely past said tongue when folded to said non-projecting position, the inherent resiliency of the material of the box serving to cause said bendable tongue to spring to said normal position after movement of said wall end portion therepast, whereby said tongue is caused to project beyond said wall end portion so as to obstruct movement of said last folded wall to collapsed condition, and means for locking the first folded wall in upstanding position.

4. A paper board box having a bottom wall and relatively transversely extending tubular side walls, said side walls being foldably connected to said bottom wall and being foldable, one in advance of the other, from collapsed condition substantially flatwise of the bottom wall to distended tubular condition in upstanding relation to said bottom wall, means for locking one of said side walls in upstanding position comprising a tongue carried by and normally projecting laterally inwardly from the first foldable wall, said tongue being bendable to substantially non-projecting position relative to the wall from which it normally projects, the other of said walls having an end portion terminating in proximity to the plane of said tongue when bent to said non-projecting position and being adjustable to upstanding position by movement transversely past said tongue when folded to said non-projecting position, the inherent resiliency of the material of the box serving to cause said bendable tongue to spring to said normal position after movement of said wall end portion therepast, whereby said tongue is caused to project beyond said wall end portion so as to obstruct movement of said last folded wall to collapsed condition, and means for locking the first folded wall in upstanding position.

to said normal position after movement of said wall end portion therepast, whereby said tongue is caused to project beyond said wall end portion so as to obstruct movement of said last folded wall to collapsed condition, and means for locking the first folded wall in upstanding position comprising a rigid tongue projecting from the last folded wall and insertable into the adjacent end portion of said first folded wall as an incident to the folding of the last folded wall to upstanding position.

5. A paper board box according to claim 1 wherein the bendable tongue is bendable on a fold line which extends transversely of the upwardly extending plane of the upstanding wall 15 held against unfolding movement by said tongue.

6. A paper board box according to claim 1 wherein said bendable tongue is foldably connected to an upper, horizontal edge portion of the wall from which it extends, and wherein said tongue is bendable downwardly from said upper edge and into face to face relation with said wall to permit the other wall to move past said tongue to upstanding position.

7. In a collapsible paper board box, a bottom wall, relatively transversely extending tubular side walls, said side walls embodying spaced inner and outer side portions and a top portion, said side portions being foldably connected adjacent their lower edges to said bottom wall, and said top

portion being foldably connected to the upper edges of said side portions, said tubular walls being foldable from a collapsed position flatwise of said bottom wall to distended tubular upstanding position, and means for locking said tubular walls in upstanding position, comprising a tongue projecting transversely from each of said walls into the end portion of the other, said tongues projecting from the respective walls in substantially parallel relation to said bottom, and being of substantial width in said parallel plane at their respective points of connection with the walls from which they extend, said tongues being thereby effective to offer substantial resistance to unfolding movement of the respective walls into which they project, one of said tongues extending from the top portion of one wall and the other of said tongues being foldably connected to a portion of the other wall, and being displaceable from normal locking position to a predetermined folded position, to permit unfolding movement of one of said walls through the locking position normally occupied by the displaceable tongue, the normal resiliency of the paper board serving to cause said displaceable tongue to automatically spring to its locking position in the last mentioned wall when unfolded to its normal upstanding position.

MILTON A. SMITH.
